(57) **CLAIM**

The ornamental design for a beverage can cooler, as shown and described.

DESCRIPTION

FIG. 1 is a perspective view of a beverage can cooler showing my new design;

FIG. 2 is a top plan view thereof;

FIG. 3 is a bottom plan view thereof; and,

FIG. 4 is a side view thereof, the other sides are substantially identical.

The broken lines are for illustrative purposes only and form no part of the claimed design.

1 Claim, 3 Drawing Sheets

FIG. 1

FIG. 2

FIG. 3

FIG. 4
